UNITED STATES PATENT OFFICE.

EDWIN F. BEUGLER, OF BUFFALO, NEW YORK, ASSIGNOR TO EDWARD B. HOLMES, OF BUFFALO, NEW YORK.

CUTTER-HEAD.

No. 909,741.

Specification of Letters Patent.

Patented Jan. 12, 1909.

Application filed May 16, 1907. Serial No. 374,027.

To all whom it may concern:

Be it known that I, EDWIN F. BEUGLER, a citizen of the United States, residing at Buffalo, in the county of Erie and State of New York, have invented a certain new and useful Improvement in Cutter-Heads, of which the following is a specification.

This invention relates to a stationary cutter head for cutting the croze and chamfering the end of barrel staves and the object of the invention is to produce a light, cheap, and practical device having but one chamfering knife and one crozing knife.

The invention also relates to certain details of construction, all of which will be fully and clearly hereinafter described and claimed, reference being had to the accompanying drawings, in which—

Figure 1 is a side elevation of the improved cutter head looking in the direction of the arrow V, Fig. 3, a section being taken through its supporting shaft. Fig. 2 is a side elevation of the improved cutter head looking in the direction opposite to the arrow V, Fig. 3. Fig. 3 is an edge view of the improved cutter head looking in the direction of the arrow W, Fig. 2. Fig. 4 is a section on or about line a a, Fig. 2, the shaft being shown in full. Fig. 5 is an enlarged section on line b b, Fig. 2. Fig. 6 is an enlarged transverse section on line c c, Fig. 1, showing the method of securing the chamfering knife in place. Fig. 7 is an enlarged transverse section on line d d, Fig. 1. Fig. 8 is an enlarged transverse section on line e e, Fig. 1, showing the method of securing the crozing knife in place. Fig. 9 is an enlarged detached edge view of the washer used in securing the chamfering knife in place. Fig. 10 is a bottom view of the same. Fig. 11 is a fragmentary edge view of a barrel stave after it has been operated upon by the improved cutter head, showing the croze cut therein and the inner edge of the stave chamfered.

In referring to the drawings for the details of construction, like numerals designate like parts.

The invention comprehends a split collar having enlargements to which a chamfering knife and a crozing knife are adjustably attached, and a stop for limiting the depth of the cut.

The split collar 1, is split at one side as shown at 2, in Figs. 1 and 2, and is con-

tracted around a hub 3, which is rigidly fastened by a key and a transverse bolt 4, to a supporting shaft 5. This hub 3, has a reduced portion 6, upon which the split collar is clamped by a clamping bolt 7, which passes through openings in enlargements 8. The bolt 7, is drawn up by a nut, see Figs. 1 and 2.

The collar is provided on the side about opposite the split with an enlargement 9, which is channeled or cut out on one face to form an inclined seat 10, against which a chamfering knife 11, is supported. The chamfering knife 11, is held in place by a locking bolt 12, which passes through an opening in the enlargement and forces the beveled side 13, of a washer 14, fitted on the bolt 12, against the side of the chamfering knife. The opening through which the bolt 12, passes is countersunk sufficiently to receive the washer 14, as shown in Fig. 6.

The crozing knife 15, is supported in a slot 16, formed in the opposite face of the enlargement and is fastened in place by a locking bolt 17.

By referring to Fig. 3, it will be seen that the cutting edge of the crozing knife 15, is V-shaped so as to produce the V-shaped croze shown in Fig. 11.

It will be noted by referring to Figs. 1 and 2, that the chamfering knife and the crozing knife extend at a slight angle to each other and that the chamfering knife is additionally tilted obliquely as shown in Fig. 3, so that it will chamfer or bevel the end of the stave properly.

A portion of the face of the enlargement in proximity to the cutting end of the crozing knife is cut away as shown at 18, in Figs. 2, 3 and 6, to allow the chips to fly to one side. This prevents the clogging of the crozing knife.

An enlargement 19, is formed on one side of the collar between the split 2, and the enlargement 9, which is provided with an opening extending therethrough in which a stop rod 20, is adjustably fitted. The rod 20, is locked in place by a set screw 21, and adjusted by an adjusting screw 22, which bears against its inner end. The adjusting screw 22, is fastened in place by a lock nut 23.

The outer projecting end of the rod 20, is beveled to fit the inner surface of the barrel, and by bearing against said inner sur-

face limits the depth of the croze cut, see Fig. 1, where this action is shown. This stop rod acts only during the first revolution of the barrel, that is, while the "rough cut" is being made. During the second revolution of the barrel, or while the finishing cut is being made, this stop rod does not contact with the barrel, the cutter head being limited by a stop on the machine to which it is attached.

The split collar 1, carries a stop screw 24, see Figs. 1, 2, 3 and 7, the head of which bears against a part of the bearing in which the shaft 5, is supported. This stop screw 24, affords a fine longitudinal adjustment of the split collar upon the hub 3. It is locked against involuntary movement by a lock nut 25.

I claim as my invention.

1. A stationary cutter head for chamfering and crozing the ends of barrel staves comprising a collar having an enlargement,

a chamfering knife supported on one side of said enlargement, a crozing knife supported on the opposite side of said enlargement; 25 said knives extending at an angle to each other and the chamfering knife being additionally tilted to give a bevel cut to the barrel stave and a stop rod supported from the collar at one side of said enlargement and 30 adapted to bear against the barrel stave to limit the extent of cut.

2. A stationary cutter head comprising a split collar having an enlargement about opposite the split, a chamfering knife supported on one face of said enlargement, a crozing knife supported on the other side of said enlargement, and a stop rod adjustably supported from the collar on one side of said enlargement.

EDWIN F. BEUGLER.
